SURGICAL CHISEL OR THE LIKE

Edward H. Reymann, Bronxville, N. Y., assignor to
Austenal, Inc., a corporation of New York

Application October 4, 1957, Serial No. 47,968

Term of patent 14 years

(Cl. D83—1)

Fig. 1 is a view of one side of a surgical chisel or the like embodying my new design with a portion of the chisel omitted for convenience of illustration. The other sides are substantially like the side shown;

Fig. 2 is a view of one end thereof;

Fig. 3 is a view of the other end thereof; and

Fig. 4 is a perspective view thereof on a slightly reduced scale.

The essential features of my design reside in the portions shown in full lines.

I claim:

The ornamental design for a surgical chisel or the like, substantially as shown and described.
